[57] **CLAIM**

The ornamental design for a volleyball antenna clamps, as shown.

DESCRIPTION

FIG. 1 is a perspective view of a volleyball antenna clamp showing our new design;

FIG. 2 is a side elevational view thereof;

FIG. 3 is a bottom plan view thereof;

FIG. 4 is a end view thereof as seen from the righthand side of FIG. 2;

FIG. 5 is a top plan view thereof;

FIG. 6 is a side elevational view thereof opposite to that of FIG. 2;

FIG. 7 is a perspective view of a volleyball antenna clamp showing an alternate form of our invention;

FIG. 8 is a side elevational view thereof;

FIG. 9 is a bottom plan view thereof;

FIG. 10 is a end view thereof as seen from the righthand side of FIG. 8;

FIG. 11 is a top plan view thereof; and,

FIG. 12 is a side elevational view thereof opposite to that of FIG. 8.
